(57) **CLAIM**

The ornamental design for a light fixture lens, as shown and described.

DESCRIPTION

FIG. 1 is a front perspective view of the light fixture lens; FIG. 2 is a bottom view thereof; FIG. 3 is top view thereof; and FIG. 4 is a first end view thereof; FIG. 5 is a second end view thereof; FIG. 6 is a front view thereof; and, FIG. 7 is an enlarged partial perspective of the right end of the lens which is a mirror image of the left end thereof. The broken lines shown in the drawings are for illustrative purposes only and form no part of the claimed design.
